[57] ABSTRACT

An electrical switch, preferably a small or miniature switch, with a double toggle, with at least one stationary pivot, two fixed contacts, one movable contact and a movable actuating member, wherein a plurality of single toggles are nested one inside the other, so that each member is simultaneously a component of at least two individual toggles, means for providing that the condition "contact pressure zero" is not possible as a permanent condition at the fixed contacts.

FIG. 1

FIG. 2

FIG.3

FIG. 4

1
ELECTRICAL SWITCH

The present invention concerns an electrical switch, preferably a small or miniature switch, with a double toggle action, having at least one fixed pivot, two fixed contacts and a movable contact, and a movable actuating member.

With such switches having a double toggle action, it is basically a matter of combining two single toggles in one assembly in order to obtain two stable switching positions.

Switches which provide this requirement, are known. For example, a snap switch is known which comprises a toggle switch provided with an operating spring attached thereto and driven by means of a plunger and a return spring. The system, comprising a transmission arm and the operating spring, is set in motion before the zero point of the contact force is reached. Another well-known small or miniature switch consists of a strip of band spring arcuately curved and loaded by an adjusting member near one clamped end and at the other clamped end having at least one longitudinally extending tongue, the free end of which bears against one of the two opposed operating points.

These conventional snap switches, however, have among others, the important disadvantage that a switching position may occur, in which the contact pressure is zero and may remain so, thus reducing the life and accuracy of operation of the switch.

The object of the present invention is to construct a switch comprising a double toggle having none of the above disadvantages.

According to the present invention there is provided an electrical switch comprising a double toggle, with at least one stationary pivot, two fixed contacts, one movable contact and a movable actuating member, wherein a plurality of single toggles are nested one inside the other so that each member is simultaneously a component of at least two individual toggles, with at least two spanning members formed as pressure spring members acting in the same direction to ensure the positioning of the displaceable contact, all the substantially rigid links are pivotably connected together and only stressed in tension so that the sum on the differential ways of all the single toggles is less than the differential way of a single toggle, that the lag way is not functionally restricted and that the sum of the spring forces acting on the movable contact changes its sign during the switching operation before the actuating member reaches the point of intersection of the extension of the spanning member disposed between a movable joint and a stationary pivot joint and the actuating line so that the condition "contact pressure zero" is not possible as a permanent condition at the fixed contacts.

In order to allow such a double toggle to operate under the best conditions possible, the rigid connecting members, according to another embodiment of the invention, are combined in a lamella.

The advantages achieved by the invention reside more particularly in that a reliable, relatively simply constructed double toggle switch having a small differential way and a functionally unlimited lag can be produced. Furthermore, the double toggle of the present invention offers the essential advantage for the switching technique compared with conventional toggle switches, that the contact pressure of the movable contact on the fixed stop rather increases than de-

2

creases before the switching operation, so that the condition "contact pressure zero" is not possible as a permanent condition.

By way of example, an embodiment of the present invention is illustrated in the drawings and will be described in greater detail hereinafter.

FIG. 1 shows a schematic view of the present invention,

FIG. 2 shows a diagram of the contact pressure of the double toggle of the present invention,

FIG. 3 is a side view of a possible variant, and

FIG. 4 is a plan view of the double toggle shown in FIG. 3.

FIG. 1 shows the schematic design of a switch constructed according to the present invention wherein, for the sake of greater clarity, the switch housing, the electrical connections, the components for resetting and the like are omitted. The FIG. 1 shows a fixed pivot 1, two fixed contacts 2 and 3, a movable contact 4, two auxiliary stops 5 and 6, two joints 7 and 8 which connect the two rigid links 9 and 10, which are under tensile load and non-positively but pivotably connected to the spanning members 11 and 12 with their compression springs 13, 14. The FIG. 1 also shows a actuating line 15 along which an actuating member 16 is guided on operation. The axis of symmetry 17 of the double toggle is shown, as also angles α and β and the contact pressure P_k indicated by the arrow 18.

The mode of operation of the double toggle switch of the present invention is explained with reference to the schematic illustration in FIG. 1. If the actuating member 16 is in the position shown, the joint 7 and the movable contact 4 bear against the stops 5 and 2 because of the pressure of the two springs 13, 14. At the same time, the link 10 is stressed like the connecting member 9.

When the actuating member 16 is moved towards the axis of symmetry 17, the pressure of the joint 7 continuously decreases because of the decreasing angle α , whereas the tension in the connecting member 9 increases. During this movement of the actuating member 16, the angle β changes only very slightly, since the joint 7 is only very slightly displaced towards the actuating line 15. The torque acting in the anticlockwise direction onto the movable contact 4 remains practically constant, since the force acting through the compression spring 13 on the joint 8 increases rather than decreases. Hence the contact pressure P_k remains practically unchanged in the direction of the arrow 18. At the latest when the actuating member 16 is slightly below the point of intersection 19 of the actuating line 15 with the extension 20 of the spanning member 11, the single toggle formed by the member 11 and the connecting member 9 springs over into its second stable position so that the joint 7 rests on the auxiliary stop 6. This switching process proceeds differently in practice since the force component exerted by the link 10 on the joint 7 must also be considered. With correct dimensioning of the two compression springs 13 and 14, and also with a correctly selected distance between the stationary pivot 1 and the actuating line 15, it is quite possible to cause the single toggle comprising the parts 9 and 11, to change over before the actuating element 16 reaches the point 19. As already mentioned, this is an essential feature of the double toggle switch of the present invention. It is obvious that the single toggle formed by the link 10 and the spanning member 12 springs over

at the moment the pivot 7 passes the axis formed by the spring member 12. At the same time, the movable contact 4 suddenly jumps from the fixed contact 2 over to the fixed contact 3. A condition of "zero contact pressure" can thus never occur permanently since this condition would only be fulfilled if the joint 7 remained for a long time in the position in which the link 10 is parallel to the spanning member 13. This is impossible, since this position of the joint 7 is unstable and is traversed during the jumping-over of the single toggle 9/11. What is essential thereby is that the contact pressure P_k suddenly changes its sign and acts on the movable contact 4 in a direction opposed to the arrow 18.

FIG. 2 shows a graph of the contact pressure P_k . The contact pressure P_k is shown on the ordinate 21 and the way of the actuating member 16 on line 15, on the abscissa 22. According to this diagram, the contact pressure P_k remains at first constant during the movement of the actuating member 16, to then gradually rise somewhat until the point 23 is reached where the joint 7 (FIG. 1) intersects the axis of the spanning member 12 (FIG. 1) whereon the pressure suddenly reverses at point 24 and intersects the abscissa. After the movable contact 4 is fallen onto the fixed contact 3 (FIG. 1), corresponding to the point 25 of the diagram, the contact pressure P_k remains constant again substantially independently of the lag of the actuating member 16.

The return operation is effected in similar manner; the contact pressure P_k is practically constant again up to the point 26, in order to spring back through 27 to 28. The difference way of the double toggle as a whole, which is defined by the distance between the points 24 and 27, is equal to or, if all the parts are correctly designed, less than, for instance, the difference way of the single toggle formed by 9 and 11.

A practical embodiment of the double toggle switch of the present invention is shown in FIGS. 3 and 4, parts therein corresponding to those in FIG. 1, having the same reference numerals. The two rigid connecting members 9 and 10 (FIG. 1) have been combined into an lamella 29, but without having lost the individual characteristics. Especially joint 7, the link 9 and the link 10 are unchanged. It should be noted that the link 9 has been lengthened and its free end 9a is anchored in the switch housing 30. The actuating member 16 is a plunger, the longitudinal axis of which corresponds to the actuating line 15. The fixed pivot 1, on which the two compression springs 13 and 14 are mounted, is disposed on the edge of a carrier 31 anchored in the switch housing 30. The two joints 7 and 8 are formed by specially shaped parts of the lamella 29 and serve as bearing points for the compression springs 13 and 14. The two fixed contacts 2 and 3 are also unchanged, as well as the movable contact 4. The axis of symmetry 17 corresponds to that of FIG. 1, as also the auxiliary stops 5 and 6. The form of the lamella 29 and the arrangement of the compression springs 13 and 14 may be seen more easily from FIG. 4. It shows two recesses 32 and 33 formed in the lamella 29, which allow the positioning of the compression springs 13 and 14.

While I have illustrated and described one embodiment of my invention, I do not wish to restrict the scope of protection thereto but reserve the right to make such modifications and rearrangements as may come into the purview of the appended claims.

I claim:

1. An electrical switch comprising a double toggle system including a first and second toggle interconnected by means of a toggle joint displaceable between two opposite end positions, said toggles extending in substantially opposite directions from said toggle joint, contact means displaceable between two opposite end positions and fixed at the free end of said first toggle, an actuating member, the end opposite said toggle joint of the second toggle being suspended for displacement by means of said actuating member in a direction substantially transversal to said directions of extension of said toggles, a first pressure spring disposed between said toggle joint and a fixed point and a second pressure spring disposed between said free end of said first toggle and a fixed point respectively, each of said toggles being subject to tension stresses by said springs, and said contact means being displaceable in a direction substantially transversal to said directions of extension of said toggles, said second toggle being reversible through an unstable position from one of its said end positions into the other of its end positions upon displacement of its end opposite said toggle joint by said actuating member, and said first toggle and contact means respectively being suddenly reversible by reversal of said second toggle.

2. A switch according to claim 1, wherein said end positions of said second toggle are defined by abutment of said toggle joint against stop means.

3. A switch according to claim 1, wherein said toggles and said toggle joint are formed by substantially rigid portions and at least one by weakened portion respectively of one single leaf spring.

4. A switch according to claim 3, wherein one end of said leaf spring is clamped in the switch casing, the clamped end of said leaf spring being interconnected with said second toggle by a weakened portion forming a joint.

5. An electrical switch comprising a double toggle system including a leaf spring having one end thereof fixed at the switch housing, contact means fixed at the free end of said leaf spring, said leaf spring having two weakened portions at a distance from each other and each at a distance from said spring ends, such weakened portions forming flexible joints, a spring section between said weakened portion and a spring section between the one weakened portion and said contact means respectively, each of said spring sections forming a toggle portion, stop means within reach of said contact means and of said weakened portion located nearer to the contact means for limiting flexion movement of the leaf spring in a direction substantially transverse to the flat extension of said leaf spring, an actuating member mounted for displacement in a direction substantially transverse to the flat extension of said leaf spring between said one end of the leaf spring and its weakened portion next to this one end, a pressure spring acting between a fixed point in said switch housing and said free end of the leaf spring and a pressure spring acting between a fixed point and said weakened portion nearest to said free end of the leaf spring, each of said toggle portions forming together with one of said pressure springs a toggle system of which the one is operable by said actuating member while the other including said contact means is operable by said one toggle system.
